(57) **CLAIM**

The ornamental design for the pocket for electronic component tape, as shown.

DESCRIPTION

FIG. 1 is a rear perspective view thereof;

FIG. 2 is a front plan view thereof;

FIG. 3 is an end plan view thereof;

FIG. 4 is a side plan view thereof; and,

FIG. 5 is a rear plan view thereof.

The broken line(s) which define the bounds of the claimed design form no part thereof.

1 Claim, 3 Drawing Sheets

FIG. 1

FIG. 2

FIG. 4

FIG. 3

FIG. 5
